CATTLE MARKER WITH MEANS TO LIMIT
THE SWINGING MOVEMENT OF THE
MARKER PLATE

William F. Schacht, Huntington, Ind.; William J. Schacht, executor of said William F. Schacht, deceased, assignor to William F. Schacht, II, and Robert W. Schacht, both of Huntington, Ind.

Application September 27, 1944, Serial No. 556,014

2 Claims. (Cl. 40—3)

1

This invention is a novel improvement in cattle markers, comprising a chain adapted to encircle the horns or neck of the livestock, said chain carrying a marker plate, whereby farmers, herdsmen, or operators can readily identify same, the present invention being an improvement upon the cattle markers shown in my U. S. Letters Patents Nos. 2,327,823, dated August 24, 1943; 2,327,824, dated August 24, 1943; 2,345,292, dated March 28, 1944; and 2,345,293, dated March 28, 1944, and the markers shown in my Patent No. 2,354,617, dated July 25, 1944, and Patent No. 2,383,419, dated April 21, 1945.

Other minor objects of the invention will be hereinafter set forth.

I will explain the invention with reference to the accompanying drawings, which illustrate several practical embodiments thereof to enable others to adopt and use the same; and will summarize in the claims the novel features of construction and novel combinations of parts, for which protection is desired.

In said drawings:

Fig. 1 is a perspective view showing one form of my novel horn chain marker applied to the head of a horned animal.

Fig. 2 is an enlarged front plan view of the marker plate assembly shown in Fig. 1, and the adjacent link of the chain.

Fig. 3 is a side elevation of the assembly shown in Fig. 2.

Fig. 4 is a rear elevation of the assembly shown in Fig. 2.

Fig. 5 is a plan view of a modified marker plate assembly.

Fig. 6 is a side elevation of the assembly shown in Fig. 5.

Fig. 7 is a plan view of a still further modified marker plate assembly.

Fig. 8 is a side elevation of the assembly shown in Fig. 7.

Fig. 9 is a detail showing the means for securing the horn chain around the horns of the animal.

Fig. 10 is a front elevation of a further modified marker plate assembly.

Fig. 11 is a side elevation of the assembly shown in Fig. 10.

Fig. 12 is a rear elevation of the assembly shown in Fig. 10.

Fig. 13 is a side elevation of a still further modified marker plate assembly.

As shown in Figs. 1-4, the horn chain marker preferably comprises a chain 1 of any desired type adapted to be passed around the neck or

spaced horns of an animal, said chain having a hook 1a (Fig. 9) at one end adapted to be engaged in a link adjacent the other end of the chain and closed, said hook 1a allowing for adjustability of the chain to suit different sizes of necks or spacing of horns of various livestock. When used as a horn marker a portion of the chain 1 overlies the forehead of the animal; and centered upon the forehead of the animal is a marker plate 2 bearing indicia such as "25," said plate being secured to a link of chain 1 by means of a double hook 3, the upper eye of which is engaged in one of the links of chain 1 so as to be non-shiftable thereon.

15 The marker plate 2 is shown as being substantially elliptical in shape and bearing indicia 2a on its front face, said plate having a shank 2b extending from its upper edge of substantial width and being provided with a perforation 2c therein spaced from the upper edge, said perforation receiving the lower eye 3a of double hook 3. Shank 2b of the plate is provided with spaced tongues at opposite sides of perforation 2c rolled forward to form eyes 2d so spaced with respect 20 to the lower eye 3a of double hook 3 that the plate 2 is prevented from upturning due to the offset weight of said eyes 2d, and said plate 2 is limited as to sidewise swinging movement in the eye 3a of hook 3 since the eyes 2d of the shank 2b would engage the sides of the eye 3a. The above design of shank 2b and the eyes 2d thus tends to maintain marker plate 2 in proper centered position upon the forehead of the animal, as shown in Fig. 1, where the marker is used as 25 a horn marker.

A washer 10 is engaged in the lower eye 3a of double hook 3 normally lying behind the marker plate 2, as shown in Figs. 3-4; and depending from washer 10 is a double hook 8 having its lower eye 8b passed through a perforation 9a in a supplemental plate 9 which bears indicia 9b, such as "3" or other markings, to indicate the particular month in which the animal was born. The supplemental plate 9 itself is of distinctive 40 color corresponding with the color of the corresponding supplemental plate on the marker worn by the sire of the animal, whereby the herdsman may tell at a glance the month of birth, and the sire, of the livestock, the number "3" indicating that the livestock was born in the month of March, and the particular color indicating the sire. Similarly, the indicia "6" on the supplemental plate 9 would indicate that the livestock was born in June, and the numeral "1" would 45 indicate the livestock was born in January.

In practice the supplemental marker plate 9 might be sold to the herdsman separately from the remainder of the cattle marker assembly, or it may be sold attached to the marker. The supplemental markers 9 would be sold with different indicia thereon. Where sold separately, all the herdsman need do is to attach the upper eye 8a of the double hook 8 in the washer 10 or the hook 8 could be engaged in a link of chain 1, or in any other convenient location in the marker assembly.

With markers heretofore used, when calves were born and when cows were bred, it has been found difficult for the herdsman to recall their particular sires. In large herds it is almost impossible to keep accurate records as to when the cows were bred to certain bulls, and therefore many cows and calves have heretofore been lost by the herdsman not knowing when the cow was ready to freshen. By use of my supplemental marker plate system however the herdsman is enabled without records to breed his stock systematically and properly. For instance, a particular bull, in addition to the regular indicia on his main marker plate 2, would also carry a supplemental marker plate 9 of distinctive color. There are always more than two bulls in practically every herd and sometimes many more. For one bull, the color of his supplemental marker plate 9 may be red. When a cow is bred to the bull having a red supplemental marker 9, that cow would carry this same color (red) on its supplemental marker plate 9. If the cow was bred in January, it bears the indicia #1; if bred in February the indicia would be #2, and so forth. Thus the supplemental marker plate 9 indicates the month by number. A second bull would carry a different colored supplemental plate 9, such as yellow, black, etc., and the supplemental marker 9 of each cow bred to it would carry the same color, and the number of the month in which she was bred. When calves are born from a certain sire each calf would carry a supplemental marker 9 of the same color as the sire, and would bear the number of the month in which it was born, such as "5" if the calf was born in May. Thus when these calves are in the field the herdsman can tell at a glance in what month it was born, and from which sire it was bred. After the calf is old enough to be bred the marker 9 designating its sire is discarded and a new marker 9 is added to designate the bull to which the calf is bred. Referring to the cows that are bred by different sires, the herdsman will know at a glance when these cows are to freshen, thus often saving the life of the cow and its calves.

In the modification shown in Figs. 5 and 6, the marker plate 2, supplemental plate 9, washer 10, the horn chain 1, and the double hooks 3 and 8 are similar in all respects to that shown in Figs. 1 to 4. However, in this modification a closed ring 7 is also engaged in the lower eye 3a of double hook 3 in rear of the marker plate 2, said ring being of sufficient size to receive the snap of a halter strap (not shown) so that the animal may be tied in a stall or in fixed grazing position, said ring 7 obviating the necessity of the herdsman providing the livestock with the usual expensive leather halter at present commonly employed. Preferably the ring 7 normally lies behind the marker plate 2, but said plate may be tilted sufficiently in eye 3a to permit engagement or disengagement of the snap of the halter strap in ring 7. Also, ring 7 acts as a weight to keep

marker plate 2 in place or centered on the animal's forehead.

In Figs. 7-8 inclusive, the marker plate 2, washer 10, supplemental plate 9, double hooks 3 and 8, and ring 7 are identical in all respects with that shown in Figs. 5-6, but in this modification the chain 1 is passed through the ring 7 instead of through the upper eye of double hook 3, which latter has its lower eye 3a dropped down between the spaced eyes 2d of the shank of plate 2, the offset weight of eye 3a further serving to keep the plate 2 from up-ending in the double hook 3. Ring 7 being loosely and shiftably mounted on the horn chain 1, the combined weight of the plate 2, supplemental plate 9, washer 10 and double hooks 3 and 8 tend to keep the ring 7 centered on the animal's forehead.

In Figs. 10-11-12, a further modification is shown in which the double hook 3 is engaged in a link of chain 1, and in its lower eye 3a is suspended the ring 7. The marker plate 2 is suspended from the ring 7 by having its spaced eyes 2d hooked over the upper portion of ring 7 at opposite sides of the hook 3, said plate 2 normally lying in front of ring 7 as shown in Fig. 10. This construction obviates the necessity of having to provide the hole 2c in the shank 2b of plate 2 as in Figs. 1-8 inclusive. In Figs. 10-12 the eyes 2d are shown as closed against the shank 2b, while in Fig. 13 the eyes are shown partly open, it being unnecessary to close the eyes tightly as the eyes cannot become disengaged from the ring unless nearly fully opened. Thus there is little likelihood of the marker plates 2 becoming lost due to opening of eyes 2d in this type of marker assembly.

In Fig. 12 the supplemental marker plate 9 is shown suspended from the ring 7 by the double hook 8, the ring 7 thus serving as a convenient support for the supplemental marker 9 as well as serving to receive a halter strap snap, and the ring 7 gives weight to the assembly to maintain same in centered position on the neck or horn chain 1. The hook 8 of supplemental plate 9 however could be inserted in any other part of the assembly, including the chain 1.

I do not limit my invention to the exact forms shown in the drawings, for obviously changes may be made therein within the scope of the claims.

I claim:

1. A chain marker for livestock comprising a chain adapted to encircle the neck or spaced horns of the livestock, an indicia plate suspended by a double hook from said chain, and means on the plate at opposite sides of the hook for limiting the swinging movement of the plate on the chain in the lateral and vertical directions, said limiting means comprising a shank of substantial length and width extending from the upper edge of the plate and having a perforation; said double hook having one eye engaging a link of the chain and its other eye engaging the perforation in said shank; and a pair of tongues extending from said shank and bent to form eyes offset forwardly of the plane of the plate and disposed at opposite sides of the perforation and closely adjacent to said other eye of the double hook.

2. For a cattle marker, an indicia plate having a shank of substantial length and width extending from the upper edge of the plate and having a perforation; a double hook having one eye engaging the said perforation in said shank; and a pair of tongues extending from said shank and bent to form eyes offset forwardly of the plane

of the plate and disposed at opposite sides of the perforation and closely adjacent to said eye of the double hook.
